FIG. 1

INVENTOR

Andrew A. Loetscher

BY *M. M. M.*

ATTORNEYS.

UNITED STATES PATENT OFFICE.

ANDREW A. LOETSCHER, OF DUBUQUE, IOWA.

COLUMN-CLAMP.

SPECIFICATION forming part of Letters Patent No. 727,651, dated May 12, 1903.

Application filed July 10, 1902. Serial No. 115,046. (No model.)

To all whom it may concern:

Be it known that I, ANDREW A. LOETSCHER, a citizen of the United States, and a resident of Dubuque, in the county of Dubuque, and the State of Iowa, have invented a new and Improved Column-Clamp, of which the following is a full, clear, and exact description.

My invention relates to column-clamps—that is, to devices used for clamping together heterogeneous masses of material, such as the panels of a column or post, staves of a tank, and analogous structures.

Reference is to be had to the accompanying drawings, forming a part of this specification, in which similar characters of reference indicate corresponding parts in all the figures.

Figure 1 is a fragmentary elevation, partly in section, showing my invention in use and employed in drawing together the loose parts 20 of a column. Fig. 2 is a fragmentary elevation taken at right angles to the view shown in Fig. 1; and Fig. 3 is a fragmentary elevation, certain parts being shown in section upon the line *x x* in Fig. 1 looking in direction of the arrows.

An endless longitudinal member 1, preferably a stout chain, is provided with a clamping mechanism for virtually lengthening and shortening said chain. The chain is placed 30 about the panels or staves 2 of the column, tank, or similar structure and is used to grip the several parts tightly together for divers purposes required in the art. Upon each end of the chain 1 are mounted blocks 3 4, preferably made of malleable iron, the block 3 being provided with a slot 5, through which passes a pivot-pin 6, engaged by the terminal link of the chain, as indicated in Fig. 1. The block 4 is provided with a hook 4^a, 40 which engages the chain, but at a point intermediate of its ends, as indicated in Fig. 1. The superfluous links 1^a of the chain may be allowed to simply hang down or may be used, if desired, for the purpose of subsequently 45 lifting the column from the bench or trestle while the glue is undergoing the drying process. The block 3 is also provided with a slot 7, larger than the slot 5, as shown more particularly in Fig. 2. The block 4 is likewise 50 provided with a slot 8, somewhat similar to the slot 7, as shown more particularly in Fig. 2.

Journalized within the blocks 3 4 are swivels 9 10, made, preferably, of steel and threaded internally. These swivels are connected by 55 a screw 11, which is provided with right and left threads 12 13, which are mated by the threads of the respective swivels. The screw 13 is rotated by means of a T-shaped handle consisting of a central stem 14 and a cross-piece 15, the central stem 14 terminating in a slotted head 16, which passes over the screw 11 and is engaged by a pivot 18. The arrangement is such that the T-shaped handle, which normally occupies such a position that the 65 central stem 14 is in axial alinement with the longitudinal screw 11, may be moved radially upon the pivot 18, so that the operative may fold the handle in different positions, thereby increasing the leverage in tightening the 70 screw the last few turns. The bearing-surfaces 19 20 of the blocks 3 4 are slightly concave, so as to readily engage either cylindrical or flat surfaces.

One important feature of my invention is 75 the fact that the chain is provided with links large enough and otherwise adapted to engage the hook 4^a for the purpose of readily taking up superfluous slack of the chain, while one end of the chain is permanently 80 connected with the pivot 6 of the block 3. The handle may be readily folded out of the way when the device is not in use.

My device is used as follows: The chain is thrown loosely around the object to be clamped, and the screw is rotated in the proper direction to move the blocks asunder to a maximum distance. The chain is next drawn as taut as may be convenient by inserting the hook 4^a in some one of the links intermediate 90 of the end of the chain. The operative next grasps the handle, turns the screw, and tightens the chain around the structure.

It will be noted that as the screw is "two-threaded" it draws the blocks together with 95 twice the usual speed of a single-thread screw.

Having thus described my invention, I claim as new and desire to secure by Letters Patent—

1. A column-clamp, comprising two blocks, 100 an apertured swivel mounted in each block, the apertures of said swivels being provided with right and left threads, a right and left hand screw working in the apertures of the

swivels of the blocks, and a flexible member having one end fixedly secured to one of the blocks and its other end detachably connected with the other block.

- 5 2. A column-clamp comprising a longitudinal chain, a block permanently connected with one of the ends thereof, a second block provided with an integral hook adapted to engage the individual links of said chain at divers points intermediate of the length thereof, said blocks being provided with slightly-concave bearing-surfaces for engaging structures of different shapes, a pair of swivels mounted within said blocks and provided with right and left threads, a screw provided with right and left threads mating the threads of said swivels, and means by which the said screw may be turned.
- 10 3. A column-clamp comprising a longitudinal chain, a block permanently connected

with one of the ends thereof, a second block provided with an integral hook adapted to engage the individual links of said chain at divers points intermediate of the length thereof, said blocks being provided with slightly-²⁵ concave bearing-surfaces for engaging structures of different shapes, a pair of swivels mounted within said blocks and provided with right and left threads, a screw provided with right and left threads mating the threads ³⁰ of said swivels, and a T-shaped handle pivotally mounted upon said screw for turning the same, and free to fold when not in use.

In testimony whereof I have signed my name to this specification in the presence of ³⁵ two subscribing witnesses.

ANDREW A. LOETSCHER.
